UNITED STATES PATENT OFFICE.

WALTER G. DIMAN AND JOHN M. KENDALL, OF MANCHESTER, NEW HAMPSHIRE.

STOKER MECHANISM.

Application filed March 16, 1921. Serial No. 452,745.

To all whom it may concern:

Be it known that we, WALTER G. DIMAN and JOHN M. KENDALL, both citizens of the United States of America, and residents of Manchester, in the county of Hillsborough and State of New Hampshire, have invented new and useful Improvements in Stoker Mechanism, of which the following is a specification.

10 This invention relates to automatic stoking mechanism and more particularly to means for crushing the fuel prior to its presentation to the stoking mechanism proper. In the firing of commercial fuels by means 15 of mechanical stokers it is desirable for efficient operation to avoid the feeding of lumps of fuel above a predetermined size and it is therefore common to pass the fuel through a suitable crushing mechanism 20 whereby to reduce the size of lumps which may be larger than the permissible maximum. The usual practice is to remove the coal from the cars or receiving bins, pass it through a crusher and then to store it 25 in a second bin preparatory to dumping it as needed into the hopper or other receiving element of the stoking apparatus. Such a procedure however is manifestly undesirable, not only from the standpoint of the 30 cost entailed in the relatively large number of handlings required, but also in many cases by reason of the additional space consumed by the secondary bin, while the added fire risk incident to the storage of finely 35 divided fuel is also an element which must be considered in carrying out the operation as described. Moreover, when stored in a secondary bin, there is more or less tendency for the larger particles of the fuel to become 40 segregated from the finer ones with resultant possibility of choking of the stoker mechanism and lack of uniformity of results when the fuel is fired.

The principal object of the present invention is to provide for overcoming, in large measure, the undesirable features usually incident to the operation of automatic stokers as above outlined, and to this end it is proposed to provide coal crushing means 45 so related to the stoking mechanism as to crush the fuel and present it directly to the stoking mechanism in consonance with the demands of the latter. The present invention is broadly applicable to mechanical 50 stokers in general, and various arrangements might well be employed for automatically

controlling the operation of the crusher device in accordance with requirements of the stoker mechanism. In fact, if desired, the crushers for a series of stokers might be 60 driven from a common source of power, the application of the drive to each individual crusher being however under the direct control of its corresponding stoker.

A preferred arrangement, however, and 65 that which is herein specifically disclosed, contemplates the mounting of a crusher device directly upon a stoker of that type employing a reciprocating ram for feeding the fuel into the furnace. With this arrangement the crushed fuel may be delivered directly in front of the ram thus eliminating one or more of the usual handlings as well as dispensing with the secondary storage bin. For actuating the crusher device, 70 advantage may be taken of the fact that the backward stroke of the ram is normally idle, and by suitably connecting the ram and crusher, the ram, on its rearward stroke may be caused to actuate the crusher device. By 75 employing an intermittent drive such as a pawl and ratchet between the ram and the crusher the latter may remain idle during the forward or feeding stroke of the ram, thus avoiding the delivery of fuel to the 80 stoker at an improper time, while also to a large extent equalizing the power consumed on the forward and rearward strokes of the ram. The crusher preferably 85 comprises toothed rolls arranged in the lower 85 portion of a hopper whose outlet is directly above the path of the stoker ram, the rolls being of such character and the teeth thereon being so arranged as to reduce the coal to the desired size for feeding to the furnace. 95

The crusher rolls in the hopper also serve as fuel delivering and agitating means whereby there is eliminated the possibility of the choking of the hopper delivery opening by the bridging of the fuel therein, 100 while by the employment of rolls of proper proportions the maximum size of the fuel particles may be fixed as desired.

A preferred arrangement of parts whereby the object of the invention may be attained is illustrated by way of example in the accompanying drawings wherein:

Figure 1 is a side elevation illustrating the various features of the present invention as applied to a stoker of well known type;

Fig. 2 is a plan view of the device shown in Fig. 1;

Fig. 3 is an end elevation of the mechanism seen in Fig. 1, portions thereof being omitted for the sake of clearness of illustration;

5 Fig. 4 is a vertical cross section on the line 4—4 of Fig. 1;

Fig. 5 is a detail cross section on the line 5—5 of Fig. 3 illustrating a form of intermittent drive employed;

10 Figs. 6 and 7 are side and end elevations respectively of a gear forming a portion of the intermittent drive; and

15 Figs. 8, 9 and 10 are views corresponding respectively to Figs. 1, 2 and 3 but illustrating a modified form of the apparatus.

Referring to Figs. 1 to 7 inclusive, the features forming the present invention are illustrated as applied to an under feed stoker of well known commercial form and having 20 the general characteristics of that illustrated in the patent to Daley, No. 733,374, July 14, 1903. As illustrated, the front wall of the boiler setting is indicated in broken lines at 1, such wall having a feed opening 2 with which is aligned a grate or retort 3 upon which the bed of fuel 4 is burned. The stoker mechanism comprises broadly a substantially cylindrical guide structure comprising the lower member 6 and the upper member 7 secured together by means of lateral flanges and having end flanges 5 whereby they are attached to the boiler setting. This cylindrical guide casing forms a fuel receiving chamber having an immovable 30 floor and extends substantially horizontally outwardly from the boiler setting and is provided at its outer extremity with a flange 5^a, to which is secured the end flange of a steam cylinder 8. This cylinder may be 35 supported if desired, upon a column or standard 8^a and is provided with a piston having a piston rod 9. The piston rod 9 extends axially of the guide casing comprising the members 6 and 7 and has secured thereto and slidably within such casing a substantially cylindrical ram 10. This ram is preferably hollow and connected to the piston rod 9 by means of a suitable nut or other fastening means 11. The lower 40 part of the member 6 is longitudinally slotted at its outer portion for the reception of a guide fin 12 which projects downwardly from and is fixedly secured to the ram 10.

As thus constructed the stoker device is substantially like those commonly employed and wherein, upon admission of steam to the steam cylinder, the ram is caused to travel along the cylindrical guide pushing any fuel which may have been deposited in front of the same through the opening 2 and into the furnace chamber.

In accordance with the present invention there is secured to the lower portion of the fin 12 a plate 13, such plate being held in place as by means of bolts 14. Projecting

outwardly from the plate 13 and substantially at right angles to the fin 12 is a bar 15 whose outer extremity is connected integrally or otherwise to a carriage 16, such carriage being mounted upon rollers or wheels 17 suitably guided by a rail 18. The plate 13 is provided near its rear end with a second outstanding arm or bar 19, such arm being arranged to diverge from the arm 15 and being connected to the carriage 16 near the rear portion of the latter. The carriage 16 is thus rigidly secured to the fin 12 and is constrained to partake of the movements of the ram.

The rear portion of the casing member 7 is provided with an opening 20 at its upper side, such opening being defined by a pair of oppositely diverging flange members 21. Resting upon the flange members 21 is a substantially rectangular box-like casing 22 having a flange 23 at its lower portion whereby such box or casing may be secured to the flange members 21 as by means of bolts 24. The box-like member 22 is also provided with a flange 25 at its upper edge to which is secured a flange projecting from the lower portion of a hopper 27.

Journalled in the lateral walls of the box-like member 22 are the parallel shafts 28, 29, such shafts serving to support within the receptacle 22 a pair of crushing rolls 30, 31, respectively. These rolls are provided with outstanding teeth such as 32, 32^a, the latter being longer if desired than the former, it being understood however, that the exact arrangement of the crushing teeth is not essential to the present invention, it being contemplated that any suitable and efficient form of crushing rolls may be employed. Fixed to the respective shafts 28, 29 are a pair of intermeshing pinions 33, 33^a, whereby the rolls 30, 31 are constrained to rotate in opposite directions.

Secured to the side of the guide casing comprising the members 6 and 7 is a plate 34, such plate having extending upwardly and outwardly therefrom a bracket member 35 upon which is rotatably supported a gear wheel 36, such gear wheel meshing with the pinion 33. The members 6, 7 of the guide casing are provided with outstanding bosses 38, 39, respectively, and secured to the outer surface of said bosses is a plate 40, such plate being retained in proper position as by means of bolts 41. Projecting laterally outward from the plate 40 is a shaft 42 which may, if desired, be formed integrally with the plate. Upon the shaft 42 are freely mounted a pair of gears 43, 44 respectively, the latter gear meshing with the gear 36 and serving to drive the latter.

The gear 43 (see Fig. 5) is provided with an annular groove 46 in its outer face, such groove being provided in its outer peripheral wall with one or more recesses 47. Within

the recesses 47 are arranged pawl members 48 pivotally secured therein by means of pins such as 49.

Projecting from the gear 44 is an annular flange or boss 50 having formed on its peripheral surface a series of ratchet teeth 51, such flange 50 with its ratchet teeth being operatively positioned within the groove 46 in the gear 43. As thus arranged the pawls 48 are adapted to cooperate with the teeth 51 for imparting movement to the gear 44 upon movement of the gear 43 in one direction but permit the gear 44 to remain at rest upon reverse rotation of the gear 43. The gear 43 meshes with a rack 45 mounted upon the carriage 16 and formed integral therewith if desired.

In the modified arrangement illustrated in Figs. 8, 9 and 10, the boiler setting 1, grate 3 and fuel bed 4 are illustrated as in the preceding figures. The cylindrical guide casing for the ram 10 with the steam cylinder therefor and the guide fin 12 projecting from the ram are also like those previously described. The fuel crushing rolls 30, 31 and the supply hopper 27 all mounted upon the flanges 21 are also similar to those previously illustrated and described.

In the modified arrangement however, the plate 13^a secured to the fin 12 is provided with an outwardly and upwardly directed arm 15^a and with a second outwardly, upwardly and rearwardly extending arm 19^a, such arms being integrally united or otherwise secured if desired, to a carriage member 100. Projecting outwardly from the carriage member 100 are brackets 101 from the lower surface of which depend spaced lugs 102 having journaled therebetween wheels 103 or rollers 103. 104 is an elevated track for supporting and guiding the rolls 103, such track being mounted upon posts or standards 105. The crushing rolls 30, 31 are mounted upon parallel shafts 28^a, 29^a respectively, provided with intermeshing pinions 33^b, 33^c respectively. The pinion 33^b is substantially similar in construction to the gear 44 previously described being provided with an annular boss having peripherally disposed ratchet teeth. Loosely mounted upon the shaft 28^a is a pinion 43^a substantially similar in construction to the pinion 43 previously described being provided with an annular recess for the reception of the boss projecting from the gear 33^b and having one or more pawls for engaging the ratchet teeth of the latter. Mounted upon the carriage 100 is a rack member 45^a whose teeth mesh with the gear 43^a whereby to rotate the latter.

In the operation of the mechanism as previously described and referring particularly to that shown in Figs. 1 to 7 inclusive, the hopper 27 will be provided with a suitable quantity of fuel and steam will be admitted to the cylinder 8 either by

means of a manually operated valve or by automatic mechanism controlled by the steam pressure in the boiler or in other desired manner. If it be assumed that a certain quantity of fuel has passed down between the crusher rolls 30, 31 and into the lower portion of the guide casing, forward movement of the ram 10 will serve to push such fuel through the feed opening 2 and into the furnace. During the forward movement of the ram the rack carriage 16 is moved forwardly therewith thus rotating the gear 43. The arrangement of the pawls 48 is such however, that upon such movement of the gear the pawls slip freely over the teeth 51 and thus no movement is imparted to the gear 44 or to the crusher rolls 30, 31. Upon completion of the feeding movement of the ram, steam is admitted to the other end of the cylinder 8, thus reTRACTING the ram 10. As the rack carriage 16 begins to move rearwardly the pawls 48 engage ratchet teeth 51 of the gear 44, thus positively rotating the latter and thereby causing the rolls 30, 31 to rotate inwardly and downwardly toward each other. Such rotation of the rolls serves not only to crush any large lumps of coal which may be engaged by the teeth 32, 32^a, but also acts in a positive manner to feed fuel down from within the receptacle 32 and to so agitate fuel in the lower portion of the hopper as to prevent any possibility of the bridging of the latter therein with consequent failure to properly feed fuel. Thus as the ram is retracted fuel is caused to fall into the lower portion 6 of the guide casing, passing through the opening 20, the fuel thus being properly positioned for engagement by the ram upon its next forward stroke.

By this arrangement fuel is crushed and fed to the stoker mechanism in exact accordance with the requirements of the latter, it being clear that if the stoker ram is slowed down by the automatic controlling mechanism usually employed, the feed of fuel thereto will be correspondingly delayed, while if the stoker mechanism is speeded up, the delivery of fuel thereto and the crushing of such fuel will be correspondingly augmented.

The operation of the device illustrated in Figs. 8, 9 and 10 is substantially similar to that above described the only substantial difference being that in the modified form the intermediate driving gears have been dispensed with.

Having thus described the invention in a preferred embodiment of the same together with the mode of operation thereof, what we claim and desire to secure by Letters Patent of the United States is:

1. A stoker mechanism comprising a fuel hopper, reciprocatory fuel feeding means adjacent said hopper, and means responsive

- to movement of said feeding means in one direction for discharging fuel from said hopper to said feeding means, said last named means being inoperative on reverse 5 movement of said feeding means.
2. In stoking mechanism including a fuel feeding device and crushing rollers for supplying the fuel thereto, means for applying power to the feeding device, and operative 10 connections between the feeding device and the rolls for intermittently actuating the latter.
3. A stoker mechanism having a reciprocatory fuel feeding ram, a fuel receptacle 15 having crushing mechanism, and means connecting said ram and said crushing mechanism whereby the latter is caused to be operated only upon the idle stroke of the ram.
- 20 4. A stoker mechanism having a reciprocatory fuel feeding ram, a hopper thereabove, a fuel crushing roll in said hopper, and connections between said ram and roll whereby the latter is rotated only in consonance with the idle stroke of the ram.
5. In stoking mechanism the combination with a reciprocable feed ram of means for reciprocating said ram, feed rolls for intermittently supplying fuel to the ram, and direct 30 connections between the ram and the rolls for transmitting power from the ram to the rolls on the idling stroke of the ram.
6. In a stoker mechanism in combination, a reciprocatory feed ram, a rack bar, a carriage 35 for supporting said rack bar, and rigid connections between said ram and carriage whereby to reciprocate the rack bar in time with the movement of the ram, and means actuated by said rack bar for depositing fuel before said ram.
7. In a device of the class described, a reciprocatory feeding ram having an outstanding guide fin, a rack bar, a carriage therefor provided with a roller, a fixed guide rail for 45 the roller and connections between said guide fin and carriage whereby to move the latter in consonance with the movement of the ram, and means actuated by said rack bar for depositing fuel before said ram.
- 50 8. A stoker mechanism having a reciprocatory ram, a fuel crushing roll, a drive pinion fast to said roll, a rack bar reciprocable with the ram, a pawl-and-ratchet means interposed between said rack bar and said pinion whereby to impart rotational movement to said pinion upon movement of said rack bar in one direction only.
9. In a stoker mechanism, a reciprocatory fuel feeding element, a hopper arranged adjacent the path of movement of said element, a roll within said hopper for controlling the 55 delivery of fuel to said element, and drive means interposed between said roll and feeding element comprising a pinion having a pawl thereon and a second pinion having a ratchet tooth for engagement by said pawl whereby said roll is rotated to deliver fuel to said element only during the idle stoker of the latter.
10. In a stoker mechanism, a reciprocatory fuel feeding element, a hopper arranged adjacent the path of movement of said element, a fuel crushing roll within said hopper for controlling the delivery of fuel to said element, and drive means for transmitting movement from said feeding element to said roll, said means comprising a pinion having an annular cavity, pawls pivoted upon said pinion and projecting into said cavity, a second pinion disposed coaxially with said first pinion, a substantially cylindrical boss projecting from said latter pinion within the cavity of said first pinion, and ratchet teeth on the peripheral surface of said boss for engagement with said pawls, said driving means being arranged to rotate said roll only during the idle stroke of said element.
11. In stoking mechanism the combination with a fuel feeding member of means for supplying the fuel thereto, said supply means being intermittently operated by the feed mechanism between fuel ejecting movements thereof.
12. A stoker mechanism comprising a feeding ram, a guide cylinder therefor, a hopper mounted upon said cylinder, a rotatable roll within said hopper, a shaft, a pair of gears mounted on said shaft, pawl-and-ratchet connections between said gears, 100 drive means interposed between one of said gears and said roll, a rack engaging the other of said gears, and means for imparting movement to said rack in time with the actuation of the feed ram.
13. A fuel feeding mechanism comprising a reciprocable ram, a hopper arranged above the path of movement of the ram, a pair of cooperating crushing rolls, shafts for said rolls journaled in said hopper, intermeshing pinions carried by said shafts, one of said pinions having a toothed boss projecting therefrom, a gear loosely mounted upon the shaft carrying said latter pinion and provided with a pawl for engaging the teeth of said boss, and a rack member engaging said gear and having fixed connection to the ram.
- Signed by us at Manchester, N. H., this 115 9th day of March, 1921.

WALTER G. DIMAN.
JOHN M. KENDALL.
